UNITED STATES PATENT OFFICE

2,028,666

CURTAIN SUPPORT

Charles P. Henry, Cranston, R. I., assignor to
James N. Henry, Providence, R. I.

Application July 27, 1935, Serial No. 33,429

5 Claims. (Cl. 156—19)

My invention relates to curtain supports of the swinging type.

The essential objects of my invention are to overcome the disadvantages due to the top-heavy construction of this type of support whereby there has been a dangerous strain upon both the pivot pin of the curtain supporting arm but also upon the bracket in which the pivot pin was mounted.

10 Other essential objects of my invention include increase of the strength of the supporting arm at the point of its pivotal connection with the bracket, and insure against possible ultimate sagging of the supporting arm.

15 It is a further purpose of this invention to increase the ring capacity of the shaft of the supporting arm, as well as to attain all the above purposes in a sightly and economically constructed device.

20 To the accomplishment of the foregoing and related ends, said invention, then, consists of the means hereinafter fully described, and particularly pointed out in the claims.

In the construction of my invention herein illustrated,

Figures 1 and 2 are a side elevation and a top plan view respectively of my curtain support,

Figure 3, a perspective view of the bracket, and

30 Figure 4, a fragmentary side elevation of a modified form of the supporting arm.

My novel device is composed of elements so devised as to adapt them to construction by casting.

35 In detail my device includes a cast supporting arm, represented in a general way by 5, comprising a horizontal shaft 6 having upon its outer end an upturned foliated hook 7, and upon its rear extremity with a hook 8. Adjacent the latter, upon the inner end portion of the shaft 6, is a vertical post 10 provided at its top with a rearwardly directed arm 11 with a depending cylindrical pivot lug 12. Parallel with the shaft and first arm is a second arm 14 integral with an intermediate portion of the post and terminating in a depending cylindrical pivot lug 15 in vertical alignment with the lug 12.

Cast integral with the post 10 and with the adjacent portion of the shaft is an ornamental guard plate 17 for curtain rings slideable on the shaft disposed in a vertical plane and integral with the post and with the portion of the shaft adjacent the latter. The plate overhangs the shaft, with which its lower edge is parallel, and is spaced therefrom, as at 18, to afford room for travel of the curtain rings upon the shaft. The hook 8 is purposed for the reception of the end ring of the ring series.

A cast bracket member 21 includes an attaching plate 22 with interspaced flat arms 23 parallel with each other. The arms 23 are provided with openings 25 for the reception of the pivot lugs 12 and 15 which are a sliding fit in the 5 openings, the arms 11 and 14 resting upon the arms 23. Perforations 26 in the plate 22 are for the reception of screws 27 for attaching the former to the casing 29 of a door or window.

A supporting arm 5 in which the hook 8 is omitted from the rear extremity of the shaft 6 is shown in Figure 4, and possesses some, but not all of the advantages of the construction shown in Figure 1. The construction which includes the hook 8 possesses the additional novel function 15 of increasing the ring capacity of the shaft 6.

The presence of a plurality of bearing arms 14 with their depending pivot lugs furnish a maximum bearing area for arms and lugs; the interspaced relation of the arms distributes the strain 20 upon the post 10; and the location of the arms above the horizontal plane of the shaft 6 insures a minimum of strain upon the bracket 21.

I claim:—

1. In a curtain support, a shaft, an upright 25 post upon the shaft, an arm upon the upper portion of the post, a pivot lug upon the arm, a second arm upon an intermediate portion of the post, and a pivot lug upon the second arm.

2. In a curtain support, a shaft, an upright 30 post upon the shaft, an arm upon the upper portion of the post, a depending pivot lug upon the arm, a second arm upon an intermediate portion of the post, and a depending pivot lug upon the second arm.

3. In a curtain support, a shaft, an upright 35 post upon the shaft, an arm in the vertical plane of the shaft upon the upper portion of the post, a depending pivot lug upon the arm, a second arm in the vertical plane of the shaft upon an 40 intermediate portion of the post, and a depending pivot lug upon the second arm.

4. In a curtain support, a shaft, an upright 45 post upon the rear portion of the shaft, a rearwardly directed arm upon the upper portion of the post, a pivot lug upon the arm, a second rearwardly directed arm upon an intermediate portion of the post, a pivot lug upon the second arm, and a forwardly directed guard plate supported by the post above the shaft and parallel 50 therewith.

5. In a curtain support, a shaft, a hook upon the rear portion of the shaft, an upright post upon the shaft adjacent the hook, arms upon the post parallel with the shaft, and pivot lugs upon 55 the arms.

CHARLES P. HENRY.
